UNITED STATES PATENT OFFICE

2,179,750

DOUBLE-ACTING AIR VALVE

Mark M. McCracken, Portland, Oreg.

Application June 30, 1938, Serial No. 216,808

1 Claim. (Cl. 137—69)

This invention relates to an improved valve and one object of the invention is to provide a valve of such construction that it will serve as a combined air release valve and also to prevent formation of a vacuum in a pipe line or liquid container. It will thus be seen that during filling of a pipe line or container air will be prevented from interfering with filling of the same and also that during emptying of the container or line a vacuum may be broken if one starts to form and the liquid caused to flow freely.

Another object of the invention is to so construct the valve that it may be very easily applied to the top of a storage tank or other place of use and to further so construct the valve that, as the tank is filled, air may pass outwardly through a discharge at the top of the valve casing and this outlet closed by a float control member before liquid can pass out through the air outlet.

Another object of the invention is to provide a release for accumulated air while the line or tank is full and in operation.

It is another object of the invention to so construct the closure for the air outlet that in case the closure should stick and fail to move downwardly as liquid is drained out of the tank an auxiliary air passage may be uncovered by downward movement of the float and thus permit air to enter the valve casing and prevent formation of a vacuum which would interfere with free flow of liquid out of the tank.

Another object of the invention is to provide a valve of this character which is simple in construction and not liable to readily get out of order.

The invention is illustrated in the accompanying drawing, wherein

Figure 1 is a sectional view taken vertically through the improved valve,

Figure 2 is a view taken transversely through the valve along the line 2—2 of Figure 1,

Figure 3 is a top plan view of the nipple through which air passes out of and into the valve housing, and

Figure 4 is a sectional view taken transversely through the valve along the line 4—4 of Figure 1.

The casing 1 of this valve is of cup-shaped formation and at its bottom is formed with a depending neck 2 formed with a threaded bore 3 or flange connection in order that this casing may be connected with a nipple leading from a pipe line or through the top of a container to be filled with liquid. The casing is open at its top

and about the open upper end of the casing is formed an outstanding circumferentially extending flange 4 through which openings are formed to receive bolts 5 by means of which a head or cap 6 is secured to the casing. A disk or lower spider 7 is located in the lower portion of the casing 1 in vertical spaced relation to the bottom of the casing and is supported in this position by arms 8 which extend between margins of the disk and walls of the casing and are formed integral therewith so that the disk will be firmly supported and maintained at the desired distance above the bottom of the casing. Referring to Figure 1, it will be seen that the disk is downwardly thickened, thus providing a depending extension 9. By so forming the disk, an opening 10 which is formed through the disk centrally thereof and in axial alinement with the bore of the neck 2 will have considerable length.

The cap 6 is formed with an upstanding and centrally located neck 11 defining a chamber 12 at the top of the casing when the cap is secured to the casing. The upper portion of the neck is internally thickened and threaded and into this threaded portion of the neck is screwed a nipple 13 carrying an outstanding circumferentially formed collar or flange 14 which bears against the upper edge face of the neck and limits inward movement of the nipple through the neck. It will thus be seen that, when a wrench is engaged about the wrench-engaging portion 15 of the nipple, the nipple may be screwed tightly into place and a tight connection formed between the neck and the nipple. If so desired, a gasket may be provided between the flange and the upper edge face of the neck to insure formation of a tight joint. A disk or upper spider 16 which is of less diameter than the pocket 12 is disposed at the lower end of this pocket and supported by webs or side arms 17 which extend between walls of the chamber or pocket and opposite side portions of the disk. These arms are formed integral with the disk and the body portion of the cap and, therefore, the disk will be firmly supported with its center opening 18 in axial alinement with the opening 10 of the disk 1. By providing the cap with the disk 16, a valve 19 consisting of a metal disk having centrally located upper and lower stems 20 and 21 may be supported, as shown in Figure 1, with the disk of the valve resting upon the disk 16 and the upper stem slidably engaged in a sleeve 22. This sleeve which serves to guide movement of the valve is located centrally of

50
55

the nipple 13 and is firmly secured in axial relation to the nipple by arms 23 extending radially between the sleeve and the nipple and formed integral therewith. Marginal portions of the 5 valve are beveled, as shown at 24, and this beveled edge portion of the valve is to seat against the valve seat 25 at the lower end of the nipple when the valve is moved upwardly its full extent. The lower stem 21 is slidably received in the 10 opening 18 of the disk 16 and is of such length that, when the valve is in engagement with the seat 25, the lower end of the stem 21 will still be engaged in the opening 18. Attention is called to the fact that both of the stems are hollow or 15 of hollow tubular formation, thus defining an air passage 26 which extends from the upper end of the tube 20 to the lower end of the tube or stem 21. The portion of the air passage 26 within the stem 21 is of greater diameter than 20 the portion within the stem 20 and adjacent the upper end of the stem 21 there have been formed side passages 27 which are closed by the upper end of the stem or shank 28 of a float 29 during upward movement of the valve and the float. 25 The float is located within the valve casing 1, and in order to cause movement of the stem or shank 28 with the float, there have been provided disks 30 and 31 rigidly carried by the stem or shank and engaging upper and lower ends of 30 the float. The lower end portion of the stem or shank 28 extends downwardly and is slidably received in the opening 10 formed through the disk 7. By this arrangement vertical movement of the float will be guided and the stem or shank 35 of the float will always move in a vertical path.

When this valve is in use, the neck 2 is connected with a nipple or other companion fastener of a pipe line or storage tank and as the pipe line or tank is filled air will move upwardly through the valve casing and pass out through the nipple 13. When liquid enters the 40 valve casing and moves upwardly therein, the float will be carried upwardly with the liquid. During this upward movement of the float, the valve will be carried upwardly until it is seated against the valve seat 25 to shut off flow of air and liquid through the nipple. During this upward movement of the valve, the upper end of the shank 28 will have first moved upwardly in the stem 21 to close the inner ends of the side 45 passages 27 and, therefore, air will be prevented from passing through these side passages and out through the tubular stem 20. While the line is in operation or filled with liquid, should there be any air accumulated it will rise to the top of the chamber formed by the casing 1, thereby lowering the level of the water in said chamber. The valve 19 will still be held in closed position by reason of the internal pressure but the float 29 will descend on the lowered 50 water level thereby opening the air passage 26 to allow the accumulated air to escape. The escaped air will permit the water level in the chamber formed by the casing 1 to rise, lifting the float 29 into place and closing the air pas-

sage 26 before any liquid may escape, thereby making it unnecessary to drain or shut off the system to release the undesirable accumulated air. When liquid is drawn from the storage tank or the like to which the valve is applied, the 5 liquid will move downwardly in the valve casing and under normal conditions the valve 19 will move downwardly with the float out of engagement with the valve seat. Air may then pass inwardly through the nipple 13 and through 10 the chamber 12 into the valve casing. It occasionally happens that the valve will stick but the float will move downwardly with the liquid and, therefore, the upper end of the shank 28 will move out of closing relation to the side 15 passages 27 and air may pass downwardly through the stem 20 and through the side ports 27 into the chamber 12 and thus prevent formation of a vacuum. It will thus be seen that even if the valve should stick formation of a 20 vacuum will be prevented and the liquid will flow freely out of the storage tank. If it is discovered that the valve has become stuck, a dislodging instrument may be passed inwardly 25 through the nipple about the sleeve 22 or the nipple may be unscrewed from the neck of the cap. The valve may then be dislodged and replaced and the nipple thus screwed back into the neck. It will also be seen that, if cleaning or replacement of the float is necessary, the 30 bolts 5 can be removed and the cap then lifted from the valve casing to permit access to the float.

Having thus described the invention, what is claimed as new is:

A valve of the character described comprising a casing having a liquid inlet at its bottom, a cap for the upper end of said casing formed with a neck and with an upper spider in the lower portion of the neck, a lower spider in the 40 casing spaced upwardly from the liquid inlet, a nipple mounted in said neck and defining an air passage, a sleeve mounted in said nipple in spaced relation to the wall thereof, a valve resting upon the upper spider and having upper and lower stems, the upper stem being slidably received in said sleeve and the lower stem being slidably engaged through said upper spider, said stems being of tubular formation to provide an auxiliary air passage and the lower stem being 45 formed with side ports leading from the lower portion of the auxiliary air passage, a float in said casing, and a shank for said float extending vertically through the same with its lower portion slidably engaged through the lower spider 50 and its upper portion slidably engaged in the lower stem of the valve and movable therein into and out of position to close the side ports, said shank having limited upward movement 55 within the auxiliary air passage whereby upon upward movement of the float the valve will be shifted upwardly into position to engage the lower end of the nipple and close the nipple.

MARK M. McCRACKEN. 65
